UNITED STATES PATENT OFFICE

WALTER A. STEARNS, OF HAMMOND, INDIANA, ASSIGNOR
TO THE UNITED STATES STEAM & IRON
FOUNDRIES, OF NEW YORK, N. Y., A CORPORATION OF NEW YORK

CAR-SILL BEARING.

Specification of Letters Patent. Patented June 23, 1914.

1,101,101.

Application filed March 23, 1914. Serial No. 826,614.

To all whom it may concern:

Be it known that I, WALTER A. STEARNS, a citizen of the United States, and resident of Hammond, in the county of Lake and State of Indiana, have invented certain new and useful Improvements in Car-Sill Bearings, of which the following is a specification.

My invention relates to railway cars and has particular reference to a novel metallic strengthening device for use in connection with wooden underframes of cars.

It is a well known fact that there are many designs of cars in service and many cars being built having wooden underframes, that is, longitudinal wooden sill members. Usually such cars are provided with a metallic body bolster and cross bearers and as many of the shocks and strains of service are transmitted to the car body through the metal body bolster, the sills at the point of connection are frequently damaged, the bolts pulling out or becoming loose, etc. This difficulty, of course, is due to the fact that the metal composing the bolster or cross bearers possesses much greater resistance to destruction or fracture than the wooden sills.

It is an object of my invention therefore to strengthen the connection between the sills and bolster by providing an increased bearing. This is secured by locating above the body bolster a bracket or saddle of considerably greater length than the width of the bolster, such strengthening member being suitably secured to the body bolster and providing for an extended bearing on the sill as well as a plurality of connections to the sill. Such a device also readily accommodates a gearing for the car truss rods.

The invention will be more readily understood by reference to the accompanying drawings, wherein,

Figure 1 is a plan view of a fragmentary portion of a wooden underframe car having my improvement applied thereto; Fig. 2 is a section on the line 2—2 of Fig. 1, and, Fig. 3 is an enlarged section on the line 3—3 of Fig. 1, the bolster being omitted.

Referring more particularly to the drawings it will be seen that a wooden under-

frame car may consist of an end sill 10, side sills 11, intermediate sills 12, and center sills 13. Connecting the various sills is a body bolster 14, of any approved form. In Fig. 55 2 only the top plate of the body bolster is shown. Mounted above the body bolster and beneath the sills is a casting consisting of a horizontal shelf 15, having a notch 16, therein, fitting snugly the top plate 14 of 60 the body bolster; a vertical web 17, from which may be projected a truss rod bracket 18. The right angled members may be strengthened by suitable webs 19, 20. Provision is made for a large number of fastening bolts 21, 22, through the sill and bolster respectively.

By the use of a device such as shown the sills are greatly strengthened at the needed point and the life of wooden underframe 70 cars is increased.

An advantage in a device such as shown is in that it may be applied to cars which have already been built thus avoiding the necessity of splicing or reinforcing such sills 75 which have been damaged.

I claim:

1. In a car underframe, the combination of wooden center and side sills, metallic cross members, and metallic reinforcing 80 members contacting said cross members and underlying said center and side sills, said reinforcing members and said cross members having interlocking engagement and said side sills being secured to said reinforcing 85 members by a plurality of bolts, whereby an extensive strain-resisting connection is formed between the sills and the cross-members, substantially as described.

2. In a car underframe, the combination 90 of wooden side sills, metallic cross-bearers, and metallic reinforcing members having interlocking engagement with said cross bearers and underlying said sills, and a plurality of bolts connecting said reinforcing members to said sills, substantially as described.

Signed at Chicago, this 19th day of March, 1914.

WALTER A. STEARNS.
